Los Angeles, Calif.

Application January 28, 1954, Serial No. 406,715

4 Claims. (Cl. 128—24.1)

This invention relates to an ozone massage device. It is an object of our invention to provide such a device which comprises a plurality of gas filled glass tubes through which electrical current flows. The tubes are disposed in close parallel proximity to each other so that arc discharges take place between the tubes along substantially their entire length. Such discharges are small in amplitude and are continuous during the time the device is in operation. This arc discharge action generates ozone and provides stimulation for the skin and muscles when applied to the human body and improves the circulation of the blood.

It is another object of our invention to provide such a massage device which is so shaped in its contours as to provide a massage portion which fits substantially all parts and members of the human anatomy in such a manner as to provide contact between all the surfaces of the massage portion of the device and the body for effective massage and stimulation.

A further object of our invention is to provide such a device which generates ozone simultaneously with providing massage and stimulation for the skin and body, the breathing of ozone freshened air providing healthful benefits for the user in addition to the ozone therapeutic massage.

Another object of our invention is to provide such a device in which the tubes are held precisely parallel to each other at all times for maximum effective arc discharge action across the surface areas between them.

A further object of our invention is to provide such a device in which the electrodes and wiring are mounted within a convenient handle in such a manner as to minimize the possibility of undesirable current flow between them.

Yet another object of our invention is to provide such a device which is rugged in construction and which can be applied repeatedly against the body with a considerable amount of pressure without breakage of the glass tubes and without damage to the construction and operation of the device.

Our invention also comprises such other objects, advantages and capabilities as will later more fully appear and which are inherently possessed by our invention.

While we have shown in the accompanying drawings and described herein a preferred embodiment of our invention, it should be understood that the same is susceptible of modification and change without departing from the spirit of our invention.

Referring to the drawings,

Fig. 1 is a perspective view of our device;

Fig. 2 is a side elevational view of the same, showing the handle portion in section;

Fig. 3 is a side elevational view of one of the glass tubes of our device;

Fig. 4 is a bottom plan view of the tubes in assembled position.

A preferred embodiment which has been selected to illustrate our invention comprises an electrical cord 10,

2

one end of which is adapted to be connected to a suitable source of electrical supply. Cord 10 contains a pair of electrical wires 11 and 12. The other end of cord 10 extends within an elongated handle 13, which may be formed of plastic or other suitable material.

The massage portion of our device comprises a plurality of glass tubes, the ends of which are disposed within handle 13. The embodiment shown in the drawings comprises four such tubes, 14, 15, 16 and 17, although any suitable number and size of tubes may be used. Tube 14, which is shown in Fig. 3 of the drawings, has one closed end 18 and a wire 19 projecting from its opposite end 20, wire 19 being connected to an electrode within the tube and adjacent end 20 thereof. Ends 18 and 20 of tube 14 extend parallel to each other and the body portion of the tube then branches out in opposite directions from the ends to form a pair of oppositely disposed loops as illustrated in Fig. 3 of the drawings.

Tube 15 is constructed in the same manner, having a closed end 21 and an opposite end 22 with a wire 23 projecting therefrom, wire 23 being connected to an electrode within end 22.

Tube 16 has a closed end 24 and an opposite end 25 with a wire 26 projecting therefrom, wire 26 being connected to an electrode within end 25. Tube 17 has a closed end 27 and an opposite end 28 with a wire 29 projecting therefrom, wire 29 being connected to an electrode within end 28.

The tubes are all constructed in the same manner and have the same contour. When they are assembled parallel to each other in the manner shown in the drawings, the upper surfaces of their respective loops combine to form a wide, gently curved surface which is adapted to be used as a massage portion to contact the human body. Its size and contour are such that it will fit against the thigh, shoulder, neck, back, arm, or almost any part of the body in such a manner as to provide smooth continuous contact with the body. When moved across the body, it provides a massaging of the flesh and muscles.

The ends of the tubes are all mounted within handle 13 in the manner shown in Fig. 2 of the drawings. The tubes are so positioned that the ends having wires projecting therefrom are positioned adjacent the closed ends of the same or adjacent tube. This is best illustrated in Fig. 4 of the drawings. This method of assembly provides a maximum amount of separation between the wires and electrodes in order to prevent any undesirable current flow between them.

The wires 19 and 26 of tubes 14 and 16 are connected to electrical wire 11 of cord 10 and wires 23 and 29 of tubes 15 and 17 are connected to electrical wire 12 of cord 10 within handle 13. The ends of the tubes having wires are mounted within tubular plastic insulators 30, with their respective wires projecting through the bottom of insulators 30.

In order to provide accurate and precisely parallel spacing of the glass tubes from each other, the tubes are assembled in a jib before they are inserted into handle 13. They are then inserted into handle 13 as a unit and handle 13 is then filled with a suitable dielectric material which is molten in a heated state and which hardens at lower temperatures to provide a permanent mounting for the ends of the tubes and to insulate the ends of the tubes and the wires from each other.

The dielectric material used is preferably one having resilience at normal and cold temperatures. It has been found that polyethylene plastic is suitable for this purpose.

The tubes are filled with gas of any suitable kind such as argon, neon, mercury, or a mixture thereof. Electrical current for the operation of our device is obtained from a suitable high voltage transformer which is not

shown in the drawings, but which may be a 9,000 volt 18 milliamperc transformer.

In order to maintain the spacing of the body portion of the tubes and to provide a sufficiently rugged construction to withstand any pressure used in massage, the corner of the loops of the respective tubes are joined together by a small amount of dielectric material as designated by the numeral 31 in the drawings. The material used is preferably polyethylene and its use between the tubes serves to maintain the even spacing of the tubes and to strengthen the assembly by providing slightly resilient junctions between the tubes.

In use, our device is connected to a suitable source of high voltage electrical supply. Current flows from wires 11 and 12 through wires 19, 23, 26 and 29 to the electrodes within the tubes. Current then flows through the gas within the tubes. Due to the close proximity of the tube surfaces a considerable amount of arc discharge takes place between the tubes, generating ozone from the surrounding air. This action is continuous during the operation of the device and is evenly spaced along the device, due to the exactly spaced separation of the tubes.

The arc discharges appear to the eye like a plurality of extremely small sparks. To the ear, they make a slight crackling sound. When the massage portion of our device is applied to the body, it causes a slight stinging or tingling sensation which stimulates the skin and blood circulation of the surfaces it contacts and provides the therapeutic benefits of ozone massage.

We claim:

1. A massage device comprising a plurality of glass tubes, each of said tubes containing gas, an electrode disposed within one end of each of said tubes, each of said tubes having its ends extending substantially parallel to each other with its body portion bent to form a pair of loops extending outwardly from said ends, said tubes being disposed in close parallel proximity to each other with a small gap between their adjacent surfaces, the ends of all of said tubes being disposed within a handle, means within said handle for spacing said tubes evenly from each other, the upper surfaces of the loops of said tubes combining to form a massage portion which is adapted to fit the contours of the human body, said device adapted to be connected to a suitable source of electrical supply to cause electrical current to flow through said tubes and arc discharges to take place across substantially the entire massage portion of said device during the time such current

flows to provide ozone massage to stimulate the skin, muscles and blood circulation of the body.

2. The subject matter of claim 1, the ends of said loops being fastened together with dielectric material to prevent displacement or breakage of said tubes.

3. A massage device comprising a plurality of glass tubes, each of said tubes containing gas, an electrode disposed within each of said tubes, each of said tubes having its ends extending substantially parallel to each other with its body portion bent to form a pair of loops extending outwardly from said ends, said tubes being disposed in close parallel proximity to each other with a small gap between their adjacent surfaces, the upper surfaces of the loops of said tubes combining to form a massage portion which is adapted to fit the contours of the human body, said device adapted to be connected to a suitable source of electrical supply to cause electrical current to flow through said tubes and arc discharges to take place across substantially the entire massage portion of said device during the time such current flows to provide ozone massage to stimulate the skin, muscles and blood circulation of the body.

4. A massage device comprising a plurality of glass tubes, each of said tubes containing gas, an electrode disposed within each of said tubes, each of said tubes being bent so that one portion thereof extends at an obtuse angle with respect to the adjacent portion thereof, said tubes being disposed in close parallel proximity to each other with a small gap between their adjacent surfaces, said bent portions combining to form a massage portion which is adapted to fit the contours of the human body, said device adapted to be connected to a suitable source of electrical supply to cause electrical current to flow through said tubes and arc discharges to take place across substantially the entire massage portion of said device during the time such current flows to provide ozone massage to stimulate the skin, muscles and blood circulation of the body.
